United States Patent Office

Des. 189,383
Patented Nov. 29, 1960

189,383

PHOTOGRAPHIC LENS OR SIMILAR ARTICLE

Clark C. Macomber, Evanston, Ill., assignor to Bell & Howell Company, Chicago, Ill., a corporation of Illinois

Filed Nov. 23, 1959, Ser. No. 58,448

Term of patent 14 years

(Cl. D61—1)

FIG. 1.

FIG. 2.

FIG. 3.

FIG. 4.

Figure 1 is a front perspective view of a photographic lens or similar article embodying my new design;

Fig. 2 is a rear perspective view;

Figure 3 is a side elevational view, the opposite side being substantially a mirror image thereof; and

Figure 4 is a front elevational view thereof.

I claim:

The ornamental design for a photographic lens or similar article, as shown and described.
